PULP DECOY

Arthur H. Risch, Milwaukee, Wis., assignor to
Pulp Reproduction Company, Milwaukee, Wis.,
a corporation of Wisconsin

Application May 10, 1947, Serial No. 747,165

2 Claims. (Cl. 43—3)

1

The present invention relates generally to improvements in the art of producing hunters' decoys, and relates more particularly to improvements in the construction and use of molded fibrous pulp decoys and the like.

A primary object of my present invention is to provide an improved molded hunter's decoy which is simple and extremely durable and compact in construction, and which may moreover be produced in a simple manner of relatively fragile, light and inexpensive material such as fibrous pulp.

Life-like imitation decoys have, for many years, been used by hunters and the like to lure ducks, geese and other game to pre-selected localities. Such decoys are naturally subjected to considerable abuse and are generally handled in an exceedingly rough manner by the hunter. For transportation to and from the selected hunting vicinity, several decoys are ordinarily indiscriminately thrown into a bag, and the bag is then carried over the hunter's shoulder and/or tossed roughly into an automobile, boat or the like. Upon arrival at the place of intended use, the decoys are customarily unloaded in a none too gentle manner and are tossed or otherwise placed in the water. During actual shooting of game lured to the selected locality by the decoys, it is not at all uncommon for shotgun pellets or the like to hit the decoys with considerable force, often penetrating the decoy bodies. Furthermore, since the decoys are frequently stored in basements and garages, they quite naturally receive considerable abuse even during closed seasons on hunting, particularly when used by children as playthings.

In view of the rough treatment and abuse usually accorded to hunters' decoys, it was customary practice until a relatively few years ago to produce such imitation decoys of wood and other more or less durable materials, but these wood and like decoys are necessarily costly due to the time-consuming care which must be exercised in carving or otherwise forming each decoy to obtain perfect balance as well as to produce a realistic figure. Consequently, in more recent years, decoys molded or otherwise formed of relatively light and inexpensive materials such as paper pulp and which may be readily produced in large quantities and at low cost have been commercially developed and have become extremely popular and extensively used by hunters. These decoys consist generally of a shell of fibrous pulp waterproofed interiorly and exteriorly and having a buoyant plate or board se-

5 cured to the bottom thereof for maintaining the decoy in upright position on the water; and although considerable exploitation and development work by persons skilled in the art has enabled manufacturers to produce molded pulp decoys which have proven highly satisfactory and acceptable in actual use and which have rendered reasonable service, these pulp decoys have nevertheless been found undesirably susceptible to 10 breakage because of the extremely rough abuse to which the relatively thin and fragile shells are subjected. It has been found, however, that the breakage in most cases occurs at projecting parts of the decoy body and particularly at the bill or 15 beak thereof.

It is therefore a more specific object of my present invention to provide an improved life-like imitation decoy of molded pulp in which the disadvantages attendant prior molded decoys 20 are obviated and wherein the number of projections subject to breakage is minimized.

Another specific object of this invention is to provide an improved hunter's decoy which may be readily produced of relatively fragile material in 25 large quantities by molding or the like, and which is moreover adapted to effectively withstand considerable abuse and hard usage. Another specific object of the invention is to provide an improved molded fibrous pulp decoy which is highly attractive and life-like in appearance, and which is composed of a minimum number of parts.

Still another specific object of my present invention is to provide an improved light-weight hollow decoy which may be readily formed primarily of inexpensive paper pulp or the like with the aid of standard pulp molding equipment at 30 low cost, and which is nevertheless exceptionally strong and durable and adapted for long and efficient service.

40 A further object of the present invention is to provide an improved hunter's decoy comprising a hollow body of relatively fragile material molded to simulate a bird, the decoy body being formed with the bill thereof integral with the breast portion.

45 These and other specific objects and advantages of the present invention will be apparent from the following detailed description.

A clear conception of the features constituting my present invention, and of the mode of constructing decoys embodying the improvement, may be had by referring to the drawing accompanying and forming a part of this specification, wherein like reference characters designate the 50 same or similar parts in the various views.

Fig. 1 is a side elevation of one of my improved decoys, the invention being shown as embodied in a typical swimming duck type of hunter's decoy; and

Fig. 2 is a central longitudinal vertical section through the decoy.

While the invention has been shown and described as being advantageously applicable to a typical aquatic duck decoy of molded pulp, it is not my desire or intent to thereby unnecessarily restrict or limit the scope or utility of the improvement, since the invention is obviously generally applicable to various types of decoys other than duck decoys, and the hollow bodies may be molded or otherwise formed of various other suitable materials. Certain subject matter shown and described herein is disclosed and claimed in the co-pending patent of Arthur H. Risch, Patent No. 2,494,631, issued January 17, 1950, for Pulp Decoy, and therefore forms no part of the present invention.

Referring to the drawing, the typical duck decoy shown therein as embodying the invention comprises, in general, a hollow molded shell of relatively fragile and light material such as paper pulp forming a body 5 having an opening 6 through which the pulp stock may be fed to the mold and through which access may be obtained for coating the shell interior with asphalt or other adhesive and waterproof material 7, the opening 6 being shown herein as formed in the substantially flat base 8; and a suitable closure for the opening 6 shown herein as comprising a flat plate or board 9 impregnated and coated with a material such as tar or pitch and snugly confined within the opening, a heat-sealed cloth or metallic foil sheet 10 adhesively secured to and covering the exposed surface of the board 9 and extending beyond the edges thereof, and a relatively thick layer of asphalt or the like 11 spread over the cloth 10 to substantially fill the recess 12 surrounding the opening 6 and effectively close and seal the opening.

The decoy body 5 may be molded of fibrous pulp in a single simple operation with the well-known type of suction molding machine, and is, of course, formed with a head 13, bill 14 and breast portion 15. In accordance with my invention, however, the bill 14, instead of being formed remote from the breast portion 15 in accordance with the usual practice, is formed integral with the breast for the major portion of the length of the bill 14 as indicated at 16, thereby substantially eliminating projecting parts which are susceptible to breakage.

By thus constructing the molded pulp decoy with the bill 14 integral with the breast 15 through the major portion of its length as at 16, the usually fragile bill or beak 14 is caused to project only at the very tip thereof, if at all, and is thus reinforced against breakage. Furthermore, the neck portion of the body shell 5 is enlarged considerably in width by such construction and in addition to being strengthened thereby, the interior of the head and neck are rendered more accessible for application of the adhesive waterproof coating 7 and inaccessible corners or cavities are minimized. Obviously the decoy may be finally completed by waterproofing and painting of the body exterior.

From the foregoing detailed description, it will

be apparent that the present invention provides an improved hunter's decoy which may be readily constructed of relatively fragile and inexpensive material in a simple manner, and which is nevertheless extremely durable and compact in construction. By the present construction, life-like hunter's decoys may be readily produced of lightweight molded pulp or the like, and such decoys are adapted to withstand considerable abuse and hard usage and to render long and efficient service despite the rather fragile nature of the material from which they are constructed. These improved decoys may obviously be produced by molding in large quantities and at extremely low cost; and as hereinabove set forth, the formation of the body with the lower portion of the bill or beak resting directly upon and formed integral with the breast through the major portion of its length substantially eliminates projecting portions and reinforces the bill as well as the head and neck portions of the decoy against breakage and additionally permits enlargement of the neck interior and eliminates internal cavities so as to insure more ready access for ease in thoroughly interiorly coating the shell. Standard pulp molding equipment may be utilized for producing the improved decoys, and decoys embodying the invention are strong, durable, light, and practical.

It should be understood that it is not desired or intended to limit this invention to the exact details of construction or to the precise mode of use or application herein shown and described, for various modifications within the scope of the appended claims may occur to persons skilled in the art to which this invention pertains.

I claim:

1. A hunter's decoy comprising, a hollow body of relatively fragile material molded to form a shell of substantially uniform thickness throughout and having an access opening therein, said shell being formed to simulate a bird having a bill and a breast portion, and said bill being formed integral with said breast portion through the major length of the bill whereby the bill is reinforced against breakage and the internal neck portion extends forwardly to a position in front of a portion of said bill.

2. A hunter's decoy comprising, a hollow body of fibrous pulp molded to form a shell of substantially uniform thickness throughout and having an access opening therein, said shell being formed to simulate a bird having a bill and a breast portion, and said bill being formed integral with said breast portion through the major length of the bill whereby the bill is reinforced against breakage and the hollow internal neck portion extends forwardly to a point lying in a vertical plane positioned between the ends of the bill.
